UNITED STATES PATENT OFFICE.

CHARLES T. JOHNSON-VEA, OF DOVER, OHIO, ASSIGNOR TO THE DOVER MANUFACTURING COMPANY, OF DOVER, OHIO, A CORPORATION OF OHIO.

DESIGN FOR AN ELECTRIC SMOOTHING IRON.

Application filed June 19, 1926. Serial No. 18,095. Term of patent 14 years.

To all whom it may concern:

Be it known that I, CHARLES T. JOHNSON-VEA, a citizen of the United States, residing at Dover, in the county of Tuscarawas and State of Ohio, have invented a new, original, and ornamental Design for Electric Smoothing Irons, of which the following is a specification, reference being had to the accompanying drawing, forming part thereof.

Figure 1 is a plan view of an electric smoothing iron showing my new design.

Figures 2 and 3 are views in rear and side elevation respectively.

Figure 4 is a front elevation.

Figure 5 is a perspective view.

It will be noted that the body of the iron is convexly rounded at the sides and point and is rearwardly inclined to slope in all directions toward the plane bottom or ironing surface.

An important feature of the invention is the heel which is provided with beveled areas, the ends of which merge with the convexly rounded sides of the iron on curved lines.

I claim:

The ornamental design for an electric smoothing iron as shown and described.

CHARLES T. JOHNSON-VEA.
